FIG. 7

UNITED STATES PATENT OFFICE

EDWARD ANDERSON, OF CHICAGO, ILLINOIS

TEMPORARY LOCKING DEVICE

Application filed September 21, 1929. Serial No. 394,258.

This invention relates to improvements in temporary locking devices of the portable type and its object is to provide means for temporarily locking hinged doors, sliding doors, show case doors, desk drawers and the like. One object is to provide a device of this type that may be used independently of the usual locking means, as a substitute locking means when none are provided, as auxiliary to the conventional locking means when desired or when such means are temporarily out of order and a device that can, due to its size, be conveniently carried in the pocket, hand grip, hand bag or in any small container.

A further object is to provide a locking device that is positive and efficient in operation, that does not in any way mar or deface the object to which it is applied, that is cheap to manufacture and that is so simple in structure that it is unlikely to get out of order.

With the foregoing and other objects in view the invention consists in the combination and arrangement of parts to be herein-after fully described, pointed out in the claims and illustrated in the accompanying drawings which form a part of this application for patent and in which—

Fig. 1 is a front view of the locking device applied to a show case, candy case, or like object.

Fig. 2 is a top plan view of Fig. 1.

Fig. 3 is a fragmentary view of the locking device, enlarged, the back plate of the casing being removed.

Fig. 4 is a vertical sectional view taken on the line 4—4 of Fig. 3.

Fig. 5 is a view in elevation of a slightly modified form of the locking device showing its application to sliding doors, which are shown in section.

Fig. 6 is a similar view to Fig. 5 but showing a very slight further modification applied to a desk or table drawer.

Fig. 7 is a view of a further slightly modified form of the device as applied to a clothes closet door, or the like.

Fig. 8 is a fragmentary view of a bar

sometimes used which is formed with two serrated edges.

Like reference characters denote corresponding parts throughout the several views.

The locking device comprises a sectional casing to which is secured a barrel through which a shaft extends that at its end, within said casing, carries a cam that may be rotated by the shaft to oscillate a dog to which one end of a spring is secured, said spring in the locked position of the device engaging with the teeth of an anchor bar received in, and extending through, the casing to lock said bar and casing together, the bar being released in one position of the said dog.

The locking device comprises a casing formed of the large rear plate 1 and the smaller plate 2, both plates being of substantially oblong formation, the plate 1 having one end 3 disposed at right angles to its main body portion, said end 3 being formed along its free edge 4 with an approximately centrally disposed notch to permit its close engagement with the barrel 5 that is secured to the plate 2, said plate 1 at the junction of its end 3 with its body portion being formed with a longitudinally extending slot 6 to permit passage of the anchor bar 7.

The plate 2 is formed with two oppositely disposed inwardly extending flanges 8, 8 which are formed with the diametrically opposed lugs 9, 9 adapted to enter corresponding slots in the plate 1 in the assembled position of said plates.

A flange 10 formed with a reduced portion 11 extends from one flange 8 something more than one half the distance to the other flange 8, said stepped flange 10, 11 permitting passage of the spring steel anchor bar 7 and forming a guide for the same in its passage through the casing, said bar being introduced through the slot 6 in the plate 1. The plates 1, 2 are secured together by the screw 12.

Extending through the barrel 5 is the rotary shaft 13 having the key hole 14 to receive the key (not shown). Fast to the inner end of the shaft 13 within the casing is the cam 15 that peripherally engages the dog 16 pivoted upon the pin shaft 17 and to said dog

- one end of the V-shaped spring 18 is secured that is supported upon said pin shaft, the free end of said spring abutting one flange 8 of the plate 2. A lug 19 fast to the end of the 5 spring 18 secured to the dog 16 is adapted for engagement with the teeth 20 of the anchor bar 7 in one position of said dog whereby to lock said anchor bar against movement in one direction relative to the casing. When the 10 dog 16 is raised by movement of the cam 15 the bar 7 is freed and may be withdrawn from the casing.
- The anchor bar is formed with an offset 21 to permit its frictional engagement with the 15 doors 22 of a candy case and with one hooked end 23 for like frictional engagement with one of said doors, Figs. 1 and 2. In Fig. 5 the hook at the end of the bar is box-shaped as at 24, the bar frictionally engaging with 20 the sliding doors 25 and the hook 24 carrying a set screw 26a for engagement with one of the doors. In Fig. 6 the device is applied to a drawer 26, the bent end 27 being received in the bolt-receiving recess 29 of the top 28, 25 the ordinary lock 30 of the drawer being probably out of order. In Fig. 7 the end 27 of the anchor bar is received in the lock recess 31 of the jamb 32 of the closet, the closet door 33 being locked shut by the device.
- 30 When the anchor bar is applied between the doors, or between a door and its jamb, or between a drawer and the desk top the barrel and casing are moved over the anchor bar into engagement with the object and then 35 locked by so disposing the shaft 13 that the dog 19 will be in engagement with the teeth 20. By providing a double row of serrations 20 the anchor bar is made a reversible, or a right and left hand, bar. Display show 40 cases, jewelry cases, candy cases and the like may be conveniently locked while the clerk or custodian is temporarily absent without the necessity of removing the goods and an added degree of safety generally may be had 45 in the cases enumerated at an instant's notice.

What is claimed is:—

1. In temporary locking devices, a sectional perforated casing, one casing section being 50 formed with a stepped flange, the other casing section terminating in a right-angularly extending portion for disposition against one of the elements to be locked, a resilient serrated anchor bar releasably received in said 55 casing and engaging said stepped flange, said anchor bar having one offset end disposed in a direction opposite to that of said right-angularly extending section portion for engagement with the other element to be locked, 60 a rotary shaft extending into said casing and formed with a key hole, a cam fast to said shaft within said casing, a pin shaft within said casing, a dog pivotally arranged upon said pin shaft in engagement with said cam, 65 a spring supported upon said pin shaft and

terminally secured to said dog, one end of said spring engaging one casing section, and a lug fast to said spring for engagement with the teeth of said anchor bar.

2. In a temporary locking device for overlapping elements, a sectional perforated casing, one casing section being formed with a stepped flange, the other casing section terminating in a right-angularly extending portion for disposition against one of the elements to be locked, a resilient serrated anchor bar releasably received in said casing and engaging said stepped flange, said anchor bar having one offset end disposed in a direction opposite to that of said right-angularly extending section portion for engagement with one end of the other element, a rotary shaft extending into said casing, a cam fast to said shaft within said casing, and a lug operatively associated with said cam for engagement with the serrations of said anchor bar.

In testimony that I claim the foregoing as my own I have hereto affixed my signature.
